WINDOW STRUCTURE

Joseph I. Levyn, Brooklyn, N. Y.

Application October 11, 1940, Serial No. 360,699

14 Claims. (Cl. 20—49)

This invention relates to a mechanism for mounting a window in a frame and is so constructed that the window may be adjusted as a double hung sliding window and yet may be safely tilted away from its normal vertical position for washing, room ventilation or like purpose.

One of the objects of the invention is to provide a vertically movable window with devices adapting the window for tilting movement on a horizontal axis and for locking the window against vertical movement when in tilted position.

A further object is to provide checking devices for the window, coacting and coordinated with the tilting and locking mechanism in such manner that a single set of control bars or strips on the window frame serves as the stationary checking and locking elements of the assembly, thereby facilitating the installation of the window and assuring the unfailing operation thereof in use.

It is a further object to provide, in a window mounting of this type, against the entrance of air or moisture into or through the window mounting.

These and other objects will appear more fully from the following description, when considered in connection with the drawings in which:

Fig. 1 is a face view of the window and frame, parts being broken away;

Fig. 2 is a vertical sectional view therethrough, showing the double hung windows in full lines in their normal vertical position;

Fig. 3 is a view similar to Fig. 2, but showing the windows moved from their normal closed position and tilted away from vertical position;

Fig. 4 is an enlarged horizontal sectional view through one of the windows on the line 4—4 of Fig. 1;

Fig. 5 is a fragmentary sectional view similar to Fig. 4, showing the parts in the positions they assume when the window is tilted away from vertical position;

Fig. 5a is a view similar to Fig. 5, showing a modification of the weather stripping between the window and supports;

Fig. 5b is another view similar to Fig. 5, showing a slight modification of the weather stripping devices at the base of the window supports;

Fig. 6 is an elevational view of the side edge of the window, parts being in section;

Fig. 7 is a vertical sectional view taken on the line 7—7 of Fig. 6;

Fig. 8 is a fragmentary view similar to Fig. 6, showing the position of the elements when the window is tilted to horizontal position;

Fig. 9 is a sectional view on the line 9—9 of Fig. 8;

Fig. 10 is an enlarged fragmentary sectional view of the upper portion of the window supporting structure;

Fig. 11 is a perspective view of the disassembled elements constituting the hinge and locking mechanism carried by the side supporting members of the window;

Fig. 12 is a perspective view of one of the side spacing members or skids;

Fig. 13 is a perspective view of one of the housings for the checking devices, looking into the outer or open face thereof, and showing a modification adapted to another form of weather stripping;

Fig. 14 is a transverse sectional view through a side edge of a window illustrating the housing of Fig. 13 and the modified form of weather stripping;

Fig. 15 is a perspective view of the housing shown in Fig. 13, with the opposite or inner face exposed; and

Fig. 16 is a detail illustrating the method of attaching the anchoring devices.

Fig. 17 is a fragmentary sectional view on the line 17—17 of Fig. 10.

Referring to Figs. 1 to 4, there is illustrated a window frame 2 formed with side channels 3 in which the upper and lower windows 4 and 6 are slidably mounted. Each window is provided at each side edge with a supporting member 8, particularly illustrated in Figs. 4—10. The supporting members are mounted permanently in the side channels or guides of the frame so that their only movement is up and down in the channels. The windows are hingedly connected to the supporting members by devices to be presently described.

Referring now to Fig. 4, it will be noted that the side edges of the window are of reduced width, the supporting members 8 constituting extensions of the sides of the window when the latter is in vertical position. The windows 4 and

6 and supporting members 8 are hingedly connected as at 10 and are formed with similarly shaped contacting faces, preferably of cylindrical or other out-of-round configuration, so that on tilting the window the supporting members 50 are forced outwardly, away from the window, the tendency being normally to retain the window and supporting members in vertical alignment.

It is preferred to face the window and supporting members with metal where these members contact. As shown, the window supports 55

are formed entirely of metal, although, as will be understood, these supports may be formed of wood or other material. In the embodiment shown, each edge of each window is provided with an edge channel or facing formed with an arcuate portion extending across the outer edge of the window and with side flanges embracing the window to reinforce and strengthen the window and to retain the facing securely in place. The facing for the window edge and the supporting member may be formed with one or more cooperating ribs and depressions 14, two being illustrated at each edge of each window, to more tightly close the space between the window and its supports when the window is in its normal vertical position.

It will be understood that there may be substituted for the ribs and depressions 14 a flexible sealing strip 14a as illustrated in Fig. 5a.

The devices for supporting and controlling the window and its movements in the frame are particularly arranged so that one pair of control bars or strips 16 can be utilized for every function of the window, that is, the mounting as well as the control of its movements. The strips 16 extend through the major portions of the guide channels 3 of the window frames 2. The strips are secured at their ends, preferably by a reverse bent attachment element 18 to space the strips from the frame. Elements 18 are secured as at 19 to the inner face of the window frame and at 20 to the ends of the strips 16. The strips 16 are preferably formed of non-corrosive metal, for example, brass, and are formed with a succession of small, closely spaced apertures 22 for receiving the locking elements of the window control. The apertures 22 in the strips 16 are placed sufficiently close together that where the window is stopped at a point such that the pins 36 engage between the apertures therein, an upward movement of one side of the window and a downward movement of the other side will still securely lock the window and prevent it from falling out of the frame. The window can then be tilted to its normal vertical position thereafter, even though the pins on opposite sides of the window were not in corresponding holes in their respective strips. The openings in strips 16 for receiving attachment screws 20 are preferably in the form of transverse slots 20a (Fig. 17), to permit centering of the strip.

Each of the supporting members 8 of each window is formed with hinging devices indicated generally at 10, checking devices indicated generally at 24, and spacing or skid devices 26. These elements may be independently secured to the support 8, but it is preferred to construct each so that it will pass into the channel constituting the support 8 and beneath the flanges thereon, to be held against lateral displacement. The various elements constituting the control devices for the window may then be linked together so that, on securement of the central hinge elements to the channel, all of the parts will be held in assembled position, as will be more fully described.

Referring now particularly to Figs. 6-11, the hinging devices include a hinge pin or lug 28 formed with a cylindrical portion 29, cam projections 30, and an out-of-round extension 31. The locking collar 32 is passed over the cylindrical portion 29 and is formed with cams 34 coating with the cams 30 of the hinge pin for maintaining the collar 32 in inoperative position when the cams coincide. The collar 32 is formed with one

or two locking pins 36 (two being shown) constructed to engage in the openings 22 in the control strip when the collar is in extended position. The collar is formed with end extensions 38 fitted 5 in guide slots 40 of the block 42 when the parts are assembled. The block 42 is constructed to be permanently and immovably mounted in the supporting member 8, being held immovably against the said supporting member by engagement therewith of a shoulder forming the cylindrical portion 29 of the attachment pin 28, and being further locked against movement by projections 44 extending through openings formed 10 in the support 8. A spring 46 is mounted in the base of the block 42 and exerts pressure on the collar 32 to force it outwardly when the cams 30 and 34 permit. The base of the pin 28 is screw-threaded for receiving an attachment screw 48 for connecting the hinge pin 28 to a block 50 15 permanently mounted on the window sash. The block 50 has a base portion 52 whereby it is secured to the window, and a hollow cylindrical projection 54 for receiving a spring 56 and collar 58, the position of the latter being controlled by adjustment of the screw 48.

The reduced extension 31 of the hinge pin 28 is formed with flat surfaces or other out-of-round configuration corresponding with that of the central opening of block 50. The pin 28 will therefore be turned with the window 4, thus turning the cam surfaces 30 away from contact with the cams 34 to permit the collar 32 to be moved outwardly into locking position, through the force of the spring 46, when the window is turned away 20 from vertical position. The parts are held assembled with the supporting members 8 pressed firmly against the window 4 or 6, through the force of the relatively stronger springs 56.

It has been found unnecessary to supply window 25 weights for most household windows where checking devices of the type herein disclosed are employed. The checking devices as herein disclosed comprise a housing 60 formed with a hollow interior recess 62 for receiving the cam member 64. This cam member is preferably formed as an open U-shaped spring member, with the bend of the "U" at the base, and with the upper free edge inclined outwardly toward the supporting member 16. A roller 66 engages with cam member 64 and control strip 16, so that, as the window is lowered, the roller moves up the inclined surface of the cam, with the result that the friction between the roller and the strip 16 opposes downward movement of the window. On upward movement of the window the roller moves to inoperative or non-checking position. The housing 60 is formed with extensions 68 embracing the control strip 16, so that the position of the strip with respect to the checking devices and locking devices is made certain. The ends of the housings 60 are cut away as at 70 for receiving the anchoring links 72 secured to the block 42 for positioning the checking devices with respect to the hinging assembly.

The resilient spacing members 26 may be of general arch formation, with the end extensions 74 and 75 shaped generally to fit the interior of the supporting member 8 and to be engaged beneath the side flanges 26 thereof. The main body of the spacing members are formed as resilient strips 76 for yieldingly engaging the inner face of the guide channels formed in the window frame. The projections 74 and 75 are recessed to receive the supporting strips 16 and their attachment devices. The end 75 may con-

veniently be secured in the assembled window support by forming a slotted extension 78 thereon for receiving an anchoring link 79, anchored respectively to the spacing member 26 and housing 60 of the checking devices 24.

It will be seen that two assemblies of checking devices and spacing elements are provided, one set above and the other below the hinging assembly, for assuring uniform operation thereof.

Since the window-checking devices 24 normally require some slight movement of the window before they become fully effective, means are provided for locking the upper window 4 independently in its uppermost position. This may comprise a snap spring device 80 secured to the housing 60 of the checking device 24 and formed with a projecting end 82 engaging against and above the control strip 16 or its mounting bracket 18 when the window is in its uppermost position.

The supporting members 8 may be weather-stripped with respect to the window frame and guide channels thereof, if preferred. As shown in Fig. 4, the supporting members 8 are formed completely of metal. Near the outer edges of the side flanges of these members there are formed outwardly extending projections 84, in position to engage against corresponding shoulders 86 on the parting strip and molding formed at the sides of the channels. As shown, the parting strip and molding are formed with grooves 88 of sufficient width that the supporting members 8 can be moved outwardly or inwardly to the extent of their normal movement when the window is tilted. This is illustrated in Figs. 4 and 5, showing the supporting member in its normal position, with the window vertical (Fig. 4), and in its extended position, with the window tilted (Fig. 5).

The weather-stripping effect of the projections 84 and 86 can be increased, if desired, by placing a thin strip of metal over the exposed face of the parting strip, as shown in Fig. 5b, the metal facing 90 being formed of springy material and having edges 92 engaging against the sides of the supporting member 8 or the ribs 84, if employed.

A modified form of weather stripping is shown in Fig. 14. In this form the metal strip 94 is permanently mounted in the base of the window channel and may include both the side projections 95 and intermediate projecting ribs 98, the former engaging substantially against the outer face of the supporting member and the latter extending into the interior of the supporting members for engagement with the flange on the inner face of the supporting members 8. It will be understood that in this construction the housing 60 of the checking devices will be formed with corresponding grooves 99 (Fig. 13) for accommodating the intermediate projections 98. It will also be understood that the checking devices herein disclosed could be omitted and counter weights or springs utilized instead. The checking devices are particularly adaptable to the present construction, however, since they can be made to coact with the same control bar as the locking devices.

From the above description it will be seen that the devices can be assembled by sliding the housing for the checking devices and the end spacing elements into the ends of the channel constituting the supporting members, these elements being anchored to the hinging devices by the straps, as shown. Attachment of the hinge pin

in place then secures all of these parts against longitudinal movement.

In the operation of the window it can be moved upwardly and downwardly in the manner of a double hung window. For washing purposes or for ventilation or repair, the window can be moved away from closed position and then rotated on a horizontal axis to any desired position. When the window has been moved out of vertical position, the locking devices serve to prevent any upward or downward movement of the supporting members, so that the window cannot fall out of its frame. Movement of the window to its vertical position again moves the locking devices to inoperative position. Upward movement of the window is substantially unobstructed, but in downward movement thereof the checking devices are brought into operation and bear the weight of the window. Since all of the checking and locking devices operate in connection with the identical locking bars in the window frame, which locking bars are guided with respect to the window supports, all of these parts must necessarily remain in position for uniform and unfailing operation.

The window herein disclosed is readily moved upwardly or downwardly in the frame, due mainly to the employment of the resilient members or skids 26. These members have several functions. They accommodate the movement of the side supporting members 8 when the window or sash is tilted away from vertical position. In addition they center the window in the frame, make up for any variation in the width of the window or frame, prevent binding in case the wood should swell, and finally they serve as skids or anti-friction supports during movement of the window.

This application constitutes a continuation in part of my previous application, Serial No. 204,972, filed April 29, 1938.

Having now described my invention, I claim:

1. A device for mounting a window in a frame comprising a supporting member arranged to be hingedly secured to the window and to be mounted for sliding movement in said frame, an elongated control strip adapted to be secured to the frame, a friction mechanism mounted on said supporting member and formed with a friction element movable out of and into operative frictional engagement with said control strip during upward and downward movement respectively of said window, a locking device carried by said supporting member and formed with an engagement element movable to and from locking position with respect to said control strip, means controlled by the angular position of said window for actuating said locking device, and means carried from said supporting member extending behind and supporting said control strip in operative relationship to said friction element and locking device.

2. A device for mounting a window in a frame comprising a supporting member arranged to be hingedly secured to the window and to be mounted for sliding movement in said frame, an elongated control strip adapted to be secured to the frame, a friction mechanism mounted on said supporting member and formed with a friction element movable out of and into operative frictional engagement with said control strip during upward and downward movement respectively of said window, a locking device carried by said supporting member and formed with an engagement element movable to and

from locking position with respect to said control strip, releasable tensioning means for moving said engagement element into locking engagement with said control strip, means controlled by the angular position of said window for withdrawing said engagement element from locking position on movement of said window to its normal vertical position, and means carried from said friction mechanism extending behind and supporting said control strip in operative relationship to said friction element and locking device.

3. A device for mounting a window in a frame comprising a pair of slidable window supporting members, a pair of stationary control bars operatively associated with said supporting members, checking devices secured to said supporting members and formed with means coacting with said control bars for resisting downward movement of said window and having elements passing behind and supporting said control bars against substantial movement away from the supporting members, and locking means carried by said supporting member and movable to and from locking position with respect to said control bars.

4. A device for mounting a window in a frame for vertical sliding movement and tilting movement on a horizontal axis comprising a pair of supporting members slidably mounted on said frame and hingedly connected to the window on aligned axes, a pair of control bars secured to the frame contiguous to said supporting members, checking devices secured to said supporting members and formed with means coacting with said control bars for resisting downward movement of said window and having elements passing behind and supporting said control bars against substantial movement away from the supporting members, locking means carried by said supporting member and movable to and from locking position with respect to said control bars, and guiding means for maintaining fixed lateral relation between said supporting members and said control bars.

5. In a device for mounting a window in a frame, a pair of supporting members hingedly connected to said window, control bars secured to said frame in position to extend longitudinally along said supporting members, locking and checking devices mounted on said supporting members and engageable with and against said control bars respectively for preventing relative longitudinal movement thereof when moved to locking position and for checking downward movement of said supporting members at all times, and elements extending behind and supporting said control bars for cooperation with said locking and checking devices.

6. In a device for mounting a window in a frame, a pair of supporting members hingedly connected to said window, control bars secured to said frame in position to extend longitudinally along said supporting members, locking and checking devices mounted on said supporting members and engageable with said control bars for preventing relative longitudinal movement thereof, and elements extending behind and supporting said control bars for cooperation with said locking and checking devices, and resilient skid members adjacent the ends of said supporting members and engageable with said frame.

7. In a device for mounting a window in a frame, a pair of supporting members hingedly

connected to said window, control bars secured to said frame in position to extend longitudinally along said supporting members, locking and checking devices mounted on said supporting members and engageable with said control bars for preventing relative longitudinal movement thereof, means carried from said checking device supporting said control bars for cooperation with said checking and locking devices,

10 resilient skid members adjacent the ends of said supporting members and engageable with said frame, and means for anchoring said locking and checking devices and skid members to one another and to said supporting members.

15 8. A window structure comprising a frame having vertical guideways for a sash, a sash slidably mounted in said guideways, a strip provided with a series of spaced apertures arranged in each of said guideways, a supporting slide arranged on each vertical side edge of said sash, means carried by said supporting slides positioned to interlock with said apertured strip for holding said sash in various vertical positions, and means for pivotally connecting the sash with said supporting slide, said last-mentioned means including a pin, a cam structure carrying said pin, a spring for forcing said pin into one of the apertures in said slide and means controlled by said sash for holding said cam structure so that 30 said pin will be out of engagement with said apertured slide when the sash is in position for vertical movement.

9. In a window mounting for accommodating upward and downward movement of the window in a window frame, a side member for said window, a control bar secured to said frame in position to extend longitudinally of said side member, a checking device carried by said side member and formed with a recess, a roller in said recess, a yieldable backing cam within said recess for forcing said roller outwardly into frictional contact with said control bar during downward movement of said window, and means carried from said checking device and extending behind 45 the control bar for maintaining the control bar in operative relationship to said roller.

10. In a window mounting for accommodating upward and downward movement of the window in a window frame, a side member for said window, a control bar secured to said frame in position to extend longitudinally of said side member, a checking device carried by said side member and formed with a recess, a roller in said recess, a yieldable backing cam within said recess for forcing said roller outwardly into frictional contact with said control bar during downward movement of said window, means carried from the checking device and extending behind the control bar for maintaining the control bar in operative relationship to said roller, and means for releasably locking said window in its extreme uppermost position.

11. A device for mounting a window in a frame comprising a supporting member arranged to be secured to the window and to be mounted for sliding movement in said frame, an elongated control strip adapted to be secured to the frame, and a friction mechanism mounted on said supporting member and formed with a rotatable 65 friction element with its axis transverse of said control strip and movable out of and into operative, yieldable, frictional engagement with said control strip during upward and downward movement respectively of said window, and a member carried by said supporting member sup-

porting said control strip for engagement with said friction element.

12. A device for mounting a window in a frame comprising a supporting member arranged to be secured to the window and to be mounted for sliding movement in said frame, an elongated control strip adapted to be secured to the frame, and a friction mechanism mounted on said supporting member, formed with a rotatable friction element with its axis transverse of said control strip and movable out of and into operative, yieldable frictional engagement with said control strip during upward and downward movement respectively of said window, and a guide in fixed position with respect to said friction mechanism embracing said control strip for guiding the latter with respect to the former.

13. In combination, a window mounting comprising a stational control strip, a window support, means for hingedly connecting said support to said window comprising a bracket fixedly attached to said support, a locking element mounted for inward and outward movement on said bracket and keyed against rotation with respect thereto, said locking element cooperating with said control strip for positive locking engagement therewith, a hinge pin extending through

said locking element, bracket and support, and connected to said window for rotation therewith, cam means associated with said hinge pin and locking element for moving said locking element to unlocked position when said window is rotated to its normal vertical position, and spring means for moving said locking element to interengaging locking position with said control strip when said window is moved to any substantial extent from its normal vertical position.

14. In a window mounting for accommodating upward and downward movement of a window in a window frame member, a window side member, a control bar secured to one of said members in position to extend longitudinally of the other member, a checking device carried by said other member and formed with a recess, a roller in said recess, a yieldable backing cam within said recess for forcing said roller outwardly into frictional contact with said control bar during downward movement of said window, and means carried from said checking device and extending behind the control bar for maintaining the control bar in operative relationship to said roller.

JOSEPH I. LEVYN.
